[57] CLAIM

I claim the ornamental design for a element of a dispenser for particulate material, as shown and described.

DESCRIPTION

FIG. 1 is a front elevational view of an element of a dispenser for particulate material showing my new design;
FIG. 2 is a side elevational view thereof;
FIG. 3 is a top plan view thereof;
FIG. 4 is a rear elevational view thereof;
FIG. 5 is a side elevational view opposite FIG. 2;
FIG. 6 is a bottom plan view thereof; and,
FIG. 7 is a perspective view thereof.

The details shown in broken lines in FIG. 2 and 5 are for illustrative purposes only and form no part of the claimed design.
